[57] **CLAIM**

The ornamental design for a slide immunoassay detection system, as shown and described.

DESCRIPTION

FIG. 1 is a front elevational view of a slide immunoassay detection system showing our new design;

FIG. 2 is a left side elevational view thereof;

FIG. 3 is a right side elevational view thereof;

FIG. 4 is a rear elevational view thereof;

FIG. 5 is a top plan view thereof; and,

FIG. 6 is a front perspective view thereof.

The bottom of the slide immunoassay detection system is unornamented.

The broken line showing of rubber feet in the figures is environmental only and forms no part of the claimed design.
